UNITED STATES PATENT OFFICE.

MAX ROCKSTROH, OF KLEIN-SEDLITZ, NEAR PIRNA, GERMANY.

STIFFENING OF PRINTING PRESSES.

Original application filed October 12, 1920, Serial No. 416,585. Divided and this application filed August 15, 1921, Serial No. 492,484.

To all whom it may concern:

Be it known that I, MAX ROCKSTROH, citizen of the German Republic, residing at Klein-Sedlitz, near Pirna, Saxony, Germany, have invented certain new and useful Improvements in Stiffening of Printing Presses (for which I have filed applications in Germany, March 6, 1918; Austria, March 20, 1918; Hungary, March 18, 1918; Switzerland, March 21, 1918; Denmark, March 22, 1918; Italy, April 10, 1918; Great Britain, April 6, 1918; France, May 22, 1918), of which the following is a specification.

This invention is a division of my pending application Serial No. 416,585 filed Oct. 12, 1920 and has for its object to provide means for the correction of a defect which all printing presses exhibit after continued use, that under great strains the side frames bow out sideways at the cylinder bearings and become elastic. Even when the side frames are gripped by the base to the highest permissible limit a springing out is not entirely to be avoided.

Another object of the invention is the provision of specific means for removing this defect which is attained by connecting the side frames together in the locality of the bearings of the pressure cylinder by a tie-rod secured to the side frames and passing through the hollow axle or sleeve of the pressure cylinder.

With these objects in view the invention consists in the novel construction and arrangement of parts as will be hereinafter described and claimed.

In the drawing the figure represents a front elevation of a printing press with parts broken away showing in cross section the details of my invention.

Referring in detail to the several elements of the device, the base member *a* of the printing press is provided with side members *b* and *c* respectively secured in upright relation thereto and having near their upper ends bearing apertures *j* for the reception of the hollow sleeve or axle *l* by which the pressure cylinder *e* of the printing press is rotatably supported. The pressure cylinder *e* is adapted to co-act with the printing frame *k* which is mounted to reciprocate on roller bearings *p* mounted on the bed plate *q* of the printing press. The ends of the pressure cylinder *e* are provided

with gearing *r* by which said pressure cylinder is rotated through suitable power instrumentalities not shown. The axle *l* is apertured axially throughout its length for the reception of a tie-rod *m* which is freely insertable therethrough and projects at either end beyond the side frames *b* and *c*.

The tie-rod *m* is threaded at both ends and passes through abutment plates *o* which are made larger than the bearing apertures *j* so as to lie against the outer surface of the side frames, being held in engagement therewith by nuts *n* screwed on the threaded ends of the tie-rod. The axle *l* is preferably made of smaller diameter where it engages the bearing apertures on the side frames than that of the adjoining portion of said axle forming with said portion of larger diameter annular shoulders *s* which abut against the inner surface respectively on the side frame. Said annular shoulders co-operating together form a spacing means to prevent inward movement of the side frames and the abutment plates held in engagement with the outer surface of the side plates by the tension of the tie-rod *m* afford means to prevent outward movement of said side members.

It will be apparent that by this construction I have provided a means for rendering rigid against displacement the free ends of the side members and that the tie-rod is relieved of all strains of supporting the pressure cylinder.

It is obvious that the specification details of construction and configuration of parts described herein may be modified in various ways without sacrificing the advantages of the invention or departing from the scope thereof as defined in the appended claims.

Having described my invention what I claim as new and desire to secure by Letters Patent, is:—

1. In a printing press comprising a base and pressure cylinder, side members secured in upright position to said base, said side members being provided with aligned bearing apertures, a hollow rotatable axle mounted in said apertures, said pressure cylinder being secured to said axle and a tie-rod floatably mounted within the axle and secured to said side members.

2. In a printing press, a base, side members secured thereto having aligned bearing apertures, a pressure cylinder having an

axial cylindrical sleeve projecting at both ends therefrom, said sleeve being formed with external bearing surfaces cooperating with the bearing apertures in said side members, and a tie-rod floatably mounted within said sleeve and secured to said side members.

3. In a printing press, a base, side members secured thereto having aligned bearing apertures therein, a pressure cylinder having an axial sleeve projecting at both ends therefrom, said sleeve being formed with an end portion of reduced diameter forming an external bearing surface cooperating with the bearing apertures in the side members, said portion of reduced diameter forming with the part of larger diameter, annular shoulders cooperating with the inner surface of members therefor, and a tie-rod floatably mounted within said sleeve and secured to said side members.

4. In a printing press, a base, side mem-

bers secured thereto having aligned bearing apertures therein, a pressure cylinder having an axial sleeve extending therethrough projecting at both ends therefrom, said sleeve being formed with external bearing surfaces cooperating with the bearing apertures in the side members, a tie-rod floatably mounted within said sleeve and projecting from either end through said side members, abutment plates mounted on the ends of said tie-rod in engagement with the outer surfaces of said side members and means cooperating with the ends of said tie-rod to hold said abutment plates in position.

In testimony whereof I have hereunto set my hand in presence of two subscribing witnesses.

MAX ROCKSTROH.
